FUSE CRIMPING TOOL

Austin W. Day, Washington, D. C.

Application August 18, 1938, Serial No. 225,569

1 Claim. (Cl. 86—40)

(Granted under the act of March 3, 1883, as
amended April 30, 1928; 370 O. G. 757)

This invention relates to a fuse crimping tool, and has for an object to provide an improved tool especially adapted for crimping the jacket on a fuse.

5 A further object of this invention is to provide an improved crimping tool which crimps the upper edge of the jacket about the face thereof, firmly securing the fuse base to the fuse nose.

Still a further object of this invention is to 10 provide a crimping tool which is self-centering, eliminating the guide feature necessary in prior types of anvils.

Still a further object of this invention is to 15 provide a crimping tool which will handle bent and out of round jackets as easily and as rapidly as it does perfect ones.

With the foregoing and other objects in view, the invention consists in the construction, combination and arrangement of parts hereinafter 20 described and illustrated in the drawing, in which,

Fig. 1 is a sectional view through the anvil and punch showing the fuse and plunger in elevation.

Fig. 2 is an enlarged sectional fragmentary 25 view of the tool at the commencement of the crimping operation; and

Fig. 3 is a similar view at the finish of the crimping operation.

There is shown at 10 the crimping tool comprising the anvil 11, the punch 12, the center plunger 13 and the compression spring 14 for holding the plunger 13 in proper relative position. The anvil 11 is provided with a suitably tapered inner opening 15 to receive and support 30 the nose 16 of the fuse 17 therein, the nose 16 having a fuse jacket 18 previously crimped thereto as at 19 into a suitably formed undercut groove 20 in the nose 16. As thus placed in position the jacket 18 is substantially cone shaped in 35 outline. A fuse base 21 must be attached to the fuse nose 16 to complete the fuse.

This fuse base 21 is frusto-conical in shape, its 40 smaller end having a diameter substantially equal to that of the larger end of the nose 16, while the other end 22 of the fuse base 21 is provided with a smoothly rounded shoulder 23. The upper edge 24 of the anvil 11 is provided with a 45 degree upwardly extending surface which may join to a horizontal surface 25. The 45 punch 12 is provided with a complementary 45 degree angle surface 26 which is joined by a curvature 27 having the same radius as that of the rounded shoulder 23 of fuse base 21, and the curvature 27 joins smoothly to the horizontal 50 upper surface 28.

In operation, the punch 12 may be suitably operated for vertical reciprocation by any convenient hand or power operated mechanism. The punch 12 is raised vertically and the nose 16 with the jacket 18 crimped therein as at 19, with 5 the fuse base 21 in position, is dropped into its inner tapered opening 15 with the portion 27 of the jacket 18 left projecting thereabove. The operating mechanism is then actuated to press the punch 12 downwardly.

As the punch 12 moves downwardly the plunger 13 contacts the top 28 of the fuse base 21 and presses the fuse base downwardly tight into the jacket 18 against the nose base 16, centering it if necessary as the projecting edge portion 27 of the jacket 18 is contacted by the 45 degree surface 27' of the punch 12. The compression spring 14 then yields after the fuse base 21 is properly positioned and centered, allowing the angular surface 26 of the punch 12 to contact the extreme edge of the projecting portion 27 of jacket 18 and commences to crimp it inwardly.

As the punch 12 continues to move down, the edge of jacket portion 27 follows the radius of curvature 27' of punch 12 and passes inwardly under the horizontal surface 28' of punch 12 until finally it is crimped inwardly and smoothly in tight contact against the shoulder 23 and surface 22 of fuse base 21, as shown in Fig. 3.

The operating mechanism is then actuated to raise the punch 12 vertically, allowing the completed fuse 17 to be removed therefrom. Should, for any reason, the fuse be stuck to the anvil 11, it can be easily forced outwardly therefrom by 30 a tool inserted through the aperture in the bottom thereof. If the jacket 18 is somewhat bent or out of round or should the jacket portion 27 likewise be bent or out of round, the same will be automatically brought into proper position by 35 the pressure of the plunger 13 forcing the fuse base 21 into proper position and by the angular surface 26 cooperating with the jacket portion 27 to bring it accurately to the desired position 40 and cause it to flow about the curvature 27' under the flat surface 28' as it is crimped onto the fuse base 21. As a result thereof the procedure is greatly expedited, enabling a far greater 45 number of fuses to be assembled and united in a given period of time than was possible with 50 any known type of crimping tool.

Other modifications and changes in the proportions and arrangements of the parts may be made by those skilled in the art without de- 55

parting from the nature of the invention, within the scope of what is hereinafter claimed.

The invention described herein may be manufactured and used by or for the Government of 5 the United States of America for governmental purposes without the payment of any royalties thereon or therefor.

Having thus set forth and disclosed the nature of this invention, what is claimed is:

10 A fuse crimping tool comprising an anvil having a tapered opening to receive and support a fuse nose and conical jacket thereon, the jacket having a portion extending beyond a fuse base placed on the fuse nose, and a punch for crimping 15 the jacket portion about the fuse base to secure it to the fuse nose, said punch being pro-

vided with a tapered portion adapted to first contact the projecting jacket portion, a complementary tapered portion on said anvil, said tapered portion of the punch being joined by a curvature to the horizontal portion adapted to overlie a correspondingly curved shoulder and horizontal portion of the fuse base to crimp the fuse jacket portion about such rounded shoulder and horizontal surface of the fuse base, a plunger reciprocal within said punch and yieldable means 10 urging said plunger downwardly to contact a portion of the fuse base and force it into intimate contact with the jacket and nose before the punch contacts the fuse jacket. 5

AUSTIN W. DAY.
